CHILD'S ROCKING SEAT

Edward G. Mueller, Omaha, Nebr., assignor to Mueller, Trybus Associates Inc., Omaha, Nebr., a corporation of Nebraska

Filed Apr. 24, 1961, Ser. No. 64,872

Term of patent 14 years

(Cl. D15—6)

FIG. 1

FIG. 2

FIG. 3

FIG. 4

FIG. 5

FIG. 6

FIG. 1 is a perspective view of a child's rocking seat showing my new design;

FIG. 2 is a side elevational view;

FIG. 3 is a front elevational view;

FIG. 4 is a rear elevational view;

FIG. 5 is a perspective view from the front thereof; and

FIG. 6 is a sectional view on the line 6—6 of FIG. 3. I claim:

The ornamental design for a child's rocking seat, substantially as shown.
